UNITED STATES PATENT OFFICE.

OSKAR LASCHE, DECEASED, LATE OF BERLIN-CHARLOTTENBURG, GERMANY; BY FRITZ LASCHE, EXECUTOR, OF BERLIN-CHARLOTTENBURG, GERMANY, AND CARL GEISSEN, OF BERLIN-SCHONEBERG, GERMANY, ASSIGNORS TO KOHLENVEREDLUNG G. M. B. H., OF BERLIN, GERMANY, A FIRM.

DISTILLING OVEN.

Application filed November 15, 1923. Serial No. 675,021.

To all whom it may concern:

Be it known that OSKAR LASCHE, deceased, formerly residing at Berlin-Charlottenburg, Germany, and CARL GEISSEN, a resident of Berlin-Schoneberg, Germany, both of them citizens of the German Empire, have made an invention relating to an Improvement in Distilling Ovens (for which they have filed application in Germany, October 5, 1922), of which the following is a specification.

This invention relates to the distillation of solid fuel and similar material and more especially to a distillation oven for bituminous fuel, its particular object being to improve the working conditions of such ovens and to increase their output.

In certain distillation ovens hitherto in use the material to be subjected to distillation in order to recover the volatile constituents travels down a plurality of superposed inclined surfaces formed by truncated cones or bells, heat being applied from outside or both from the outside and the inside and the volatile products escaping either through gaps between the cones or bells into the central part of the oven or together with the heating gases into an outer zone surrounding the cones or bells and heated from without. Obviously, in this class of ovens the volatile products expelled from the solid material, while traveling through the oven are subjected to the action of the high temperature prevailing therein and are therefore liable to suffer decomposition, apart from the danger of being diluted by the products of combustion of the heating gases.

In the oven according to the present invention the material to be subjected to distillation is evenly distributed on the outer surface of a preferably cylindrical shell closed all around, means being provided for keeping and guiding the material in contact with the outer shell surface. This shell is heated merely from within, a suitable burner being for instance disposed below and axially of the shell, and the gases of combustion are allowed to escape through a stack on the upper end of the shell, so that the material under treatment as well as the volatile products expelled therefrom are protected against any contact with the heating gases and their products of combustion. On the other hand,

the volatile products, while forming under the action of the heat acting on the solid material from within, are at once withdrawn from the injurious action of the heat and are free to escape in radial direction without coming in contact with any heated surfaces. These products will thus leave the oven without suffering any decomposition. They are removed from the oven in the shortest time and on the shortest way through openings provided in the system of outer guide surfaces as soon as they are formed and are caused to pass into a chamber surrounding the oven. Means can be provided for cooling this chamber, which may further serve for separating out the dust and for effecting a preliminary cooling and which may be subdivided for fractionally exhausting the gases of distillation.

In the drawings affixed to this specification and forming part thereof an oven embodying our invention is illustrated diagrammatically in vertical section by way of example.

Referring to the drawings, *a* is an inner cylinder of refractory material, for instance chamotte, surrounded by an outer transversely corrugated shell or cylinder *b* of cast iron. The outer surface of this outer cylinder serves as heating surface for the material to be treated and is subdivided in a plurality of superposed annular zones. These zones are formed by superposed annular guide funnels *c* which cause the material to be treated to slide down in the annular space between the cylinder and the funnels according to its angle of slope. The heating cylinder *b* is arranged to revolve or to execute a rotary pendulum motion relatively to the outer guide funnels. *y* is an outer jacket surrounding the guide funnels *c* and spaced therefrom.

We may, however, also employ a stationary heating cylinder and movable guide funnels. In order that the relative motion of the cylinder *b* and guide funnels *c* be accompanied by a grinding action, we may arrange the axes of rotation of the two systems of conical surfaces eccentrically with regard to each other or we can make them adjustable eccentrically. At the upper portion of cylinder *b* vanes *d* can be provided for distributing the material to be distilled which is supplied through a chute *p*, similar vanes *e* arranged at the bottom portion of the cylinder serving

for expelling the exhausted material through the tube *t*. Intermediate the guide funnels openings *f* are provided for the escaping gases of distillation. The cylinder *b* is made 5 to revolve in a well known manner by a worm *g* acting on a helically toothed rim *r* mounted on the top edge of the cylinder *b*. The cylinder *b* is further arranged to be adjusted axially with regard to the guide funnels *c*, 10 the adjustment being effected by means of a double armed lever *s* operated by a hand wheel *k* and acting from below on the rim *r*. A gas supply pipe *i* projecting axially into the bottom portion of the cylinder *a* serves 15 for burning a mixture of gas and air, the narrow flame formed extending into the interior of the cylindrical heat accumulator and equalizer *a* closed on top by a vertically displaceable cover *v* and provided with openings *w* allowing the gases of combustion to escape between the cylinders *a* and *b* and through the stack *u*. The sectional area of 20 the passages between the narrow nozzles formed by the partial heating surfaces of cylinder *b* and the guide funnels surrounding them can be regulated by lifting or lowering the cylinder *b*. We may, however, also lift or lower each guide funnel separately, for 25 instance by means such as a hand wheel and spindle *h* actuating a double armed lever *x* acting on the guide funnel from below.

We wish to be understood that we do not desire to be limited to the exact details of construction shown and described, for obvious modifications will occur to a person 30 skilled in the art.

We claim:—

1. Oven for the distillation of solid fuel

and similar material comprising a cylindrical transversely corrugated shell arranged 40 with its axis in vertical position, means for heating such shell from within, means for forming on and in contact with the outer surface of said shell a layer of the material to be distilled and a non-heated jacket surrounding said layer forming means and spaced therefrom.

2. Oven for the distillation of solid fuel and similar material comprising a cylindrical shell, means heating such shell from 50 within, circular adjustable guiding means surrounding said shell and spaced therefrom, said guiding means serving to cause the material to be distilled to travel on and in contact with the outer surface of said shell and 55 a non-heated jacket surrounding said guiding means and spaced therefrom.

3. Oven for the distillation of solid fuel and similar material comprising a cylindrical shell, means for heating such shell from 60 within, circular adjustable guiding means surrounding said shell and spaced therefrom, said guiding means serving to cause the material to be distilled to travel on and in contact with the outer surface of said shell, 65 means for axially adjusting said guiding means relatively to said shell and a non-heated jacket surrounding said guiding means and spaced therefrom.

In testimony whereof we affix our signatures.

FRITZ LASCHE,
The Executor of the Estate of Oskar
Lasche, deceased.

CARL GEISSEN.
